UNITED STATES PATENT OFFICE

151,079

DESIGN FOR A SERVING TRAY

Victor Sherry and Harry A. Plocky, Los Angeles, and Gustave F. Plocky, South Pasadena, Calif.

Application June 24, 1946, Serial No. 130,996

Term of patent 7 years

(Cl. D44—14)

To all whom it may concern:

Be it known that we, Victor Sherry and Harry A. Plocky, citizens of the United States and residents of the city of Los Angeles, in the county of Los Angeles and State of California, and Gustave F. Plocky, a citizen of the United States and resident of the city of South Pasadena, in the county of Los Angeles and State of California, have invented a new, original, and ornamental Design for a Serving Tray, of which the following is a specification, reference being had to the accompanying drawing, forming part thereof, in which:

Fig. 1 is a perspective view of a serving tray, showing our new design;

Fig. 2 is a top view thereof; and

Fig. 3 is a side view thereof.

We claim:

The ornamental design for a serving tray, as shown.

VICTOR SHERRY.
HARRY A. PLOCKY.
GUSTAVE F. PLOCKY.
